Att'y.

UNITED STATES PATENT OFFICE.

SOLOMON FREEHLING, OF CHICAGO, ILLINOIS.

GARMENT-SUPPORTER:

SPECIFICATION forming part of Letters Patent No. 651,600, dated June 12, 1900.

Application filed April 4, 1900. Serial No. 11,490. (No model.)

To all whom it may concern:

Be it known that I, SOLOMON FREEHLING, a citizen of the United States, and a resident of Chicago, county of Cook, State of Illinois, 5 have invented certain new and useful Improvements in Garment-Supporters, of which the following, when taken in connection with the drawings accompanying and forming a part hereof, is a full and complete description, sufficient to enable those skilled in the art to which it pertains to understand, make, and use the same.

One object of this invention is to obtain a garment-supporter by means of which when 15 desired more than one garment may be secured together and attached to a supporting article of wear, as, say, in gentlemen's apparel the device may well be used to secure together the waistbands of a pair of trousers 20 and underdrawers and such device be then attached to one of the ends of a pair of suspenders.

A further object of this invention is to obtain a garment-supporter which may be readily attached to any article of wear and used 25 as a substitute for a button lost therefrom, as, say, again referring to gentlemen's apparel, the device may be readily secured to the waistband of a pair of trousers and when 30 so secured serve as a button to which one end of a pair of suspenders may be attached; and a third object of this invention is to obtain a device of the kind named which when secured to a garment and attached to a supporting 35 article of wear will not readily become detached from its position, but which may when desired be easily so detached.

A still further object of this invention is to obtain a device of the kind named which shall 40 be simple in construction, not liable to get out of order or repair, durable, and of small cost, and a device whereof its manner of operation will be suggested by its general appearance to one not familiar therewith.

45 In the drawings referred to as forming a part of this specification, and wherein a reference-letter applied to designate a given part is used to indicate such part through the several views wherever the same appears, 50 Figure 1 is a perspective view of a blank from which one of the parts of the device is formed; Fig. 2, a perspective view of the element ob-

tained by forming the blank illustrated in Fig. 1; Fig. 3, a perspective view of an element additional to the one illustrated in Fig. 55 2 and one working complementary therewith; Fig. 4, a perspective view of a pest having disks thereon forming the button and locking part of the device; Fig. 5, a top plan view of the device; Fig. 6, a side elevation of the 60 device, such device being opened, and a sectional view of a portion of a garment placed between the engaging jaws thereof; Fig. 7, a side elevation of the device, such device being closed, and a sectional view of a garment 65 placed between the jaws thereof; and Fig. 8, a vertical sectional view on line 8 8 of Fig. 7, viewed in the direction indicated by the arrows.

A is a blank. *a a* are prongs or projections 70 on blank A.

D is an aperture in blank A, formed by punching or cutting out a portion of such blank. Aperture D may be said to comprise three parts *d d' d''*. Part *d* constitutes a slot 75 in which the shank of the button E (illustrated in perspective in Fig. 4) slides when the blank A is bent up into shape, as illustrated in Fig. 2, and assembled with part B and such button E. Part *d'* constitutes an 80 opening through which part B extends, in the manner hereinafter more fully described, and part *d''* an opening through which disk *e'* of the button E extends in the operation of the device, in the manner hereinafter more fully 85 described.

d'' d' are respectively broken lines in Fig. 1, indicating the lines on which the blank A is bent to form the element shown in perspective in Fig. 2 of the drawings. 90

B is a sheet-metal part forming an element engaging with and working complementary to the element A. (Shown in perspective in Fig. 2 of the drawings.)

a' a' are prongs or projections on element or 95 part B, which are bent or formed into engaging teeth of the device, as is well illustrated in Fig. 6 of the drawings.

b is a slot in part or element B, in which slot shank *e* of the button E is readily movable longitudinally of such part. 100

b' b' are notches formed by cutting or punching out a portion of the body part of part B, and *b'' b''* are broken lines indicating

the lines on which the parts b^3 are bent over onto adjacent portions of the part or element B, as indicated by broken lines b^4 b^4 in Fig. 3, in order to insert the end thereof having 5 such parts b^3 so bent over thereon through part d' of aperture D of part A, so as to bring the notches b' b' in such part B adjacent to the perpendicular parts d^3 d^3 of part A, after which insertion the parts b^3 b^3 are again returned to their initial position, as illustrated 10 by full lines in Fig. 3 of the drawings.

E is a button having shank e fitting loosely in slot d of part A and slot b of part B, disk e', adjacent to the under side of blank B, 15 disk e², adjacent to the upper side of part B when the device is open, as in Fig. 6, and adjacent to the upper face of part A when the device is closed, as in Fig. 7, shank e³, extending through the supporting article to 20 which the device is attached, and disk e⁴, forming, with shank e³, the button holding the supporting article (as one end of a pair of suspenders) on the shank e³.

The shoulders d^5 d^5 hold the part B up adjacent to the slotted part of the element A 25 when the device is opened, as illustrated in Fig. 6.

F, Figs. 6 and 7, is a section of a small portion of an article of clothing.

30 The operation of the device is as follows: When the button E is slid to the position thereof illustrated in Fig. 6 of the drawings, the jaws of the device may be opened, as is illustrated in such Fig. 6, and an article of 35 clothing may be inserted between such jaws. The jaws are then closed and the button E slid from the position thereof illustrated in Fig. 7, at which time the ends of the part A B adjacent to the button E are between disks 40 e' e² and are held firmly together thereby, thus holding the garment F in place between the jaws of the device.

Disk e⁴ and shank e³ form a button over 45 which an article of wear having a buttonhole therein may be buttoned, as, say, an elastic or a suspender.

To unloosen the device from the garment F, the button is slid from the position thereof illustrated in Fig. 7 into substantially the 50 position thereof illustrated in Fig. 6, when the jaws are readily opened, as illustrated in said Fig. 6. In sliding the button E from the position thereof illustrated in Fig. 6 into the position thereof illustrated in Fig. 7 and back

55 again the shank e enters and leaves the slot d, but remains at all times in slot b, and the disk e passes through part d^2 of aperture D.

Having thus described my invention, what

I claim, and desire to secure by Letters Patent, is—

1. In a garment-supporter, the combination of a plate consisting of a blank provided with an aperture therethrough and formed into a perpendicular middle part, and horizontal end parts in substantially-parallel planes, the aperture in the blank forming a slot in one of the horizontal parts of the plate and an opening formed to present shoulders through the perpendicular part thereof, an additional plate extending through the widest 65 transverse part of the aperture in the perpendicular part of the first-named plate, and held adjacent to the first-named plate by the shoulders formed in the periphery of the aperture, and such additional plate provided with 70 transverse slots engaging with the perpendicular part of the first-named plate, and also provided with a longitudinally-extending slot, and a button consisting of disks and a shank, the disks adjacent to the plates, respectively, 75 when the device is closed and secured together, and the shank extending, at such time, through the slots in both plates and such button movable out of the slot in one plate, through the aperture in the perpendicular 80 part thereof and to the opposite end of the slot in the other plate; substantially as described.

2. In a garment-supporter, the combination of a plate consisting of a blank provided with an aperture therethrough and formed into a perpendicular middle part and horizontal end parts in substantially-parallel planes, the aperture in the blank forming a slot in one of the horizontal parts of the plate 90 and an opening through the perpendicular part thereof, an additional plate extending through the aperture in the perpendicular part of the first-named plate, such additional plate provided with transverse slots engaging 95 with the perpendicular part of the first-named plate, and also provided with a longitudinally-extending slot, and a button consisting of disks and a shank, the disks adjacent to the plates, respectively, when the device is 100 closed and secured together and the shank extending at such time through the slots in both plates and such button movable out of the slot in one plate through the aperture in the perpendicular part thereof and to the opposite end of the slot on the other plate; substantially as described.

SOLOMON FREEHLING.

In presence of—

ISAAC FREEHLING,
CHARLIE WUENSCH.
